UNITED STATES PATENT OFFICE.

ANDREW B. HENDRYX, OF NEW HAVEN, CONNECTICUT.

DESIGN FOR A BIRD-CAGE HOOK.

SPECIFICATION forming part of Design No. 28,157, dated January 11, 1898.

Application filed December 6, 1897. Serial No. 660,982. Term of patent 14 years.

To all whom it may concern:

Be it known that I, ANDREW B. HENDRYX, of New Haven, in the county of New Haven and State of Connecticut, have invented a new 5 Design for Bird-Cage Hooks, (Case B;) and I do hereby declare the following, when taken in connection with the accompanying drawings and the letters of reference marked thereon, to be a full, clear, and exact description of 10 the same, and which said drawings constitute part of this specification, and represent, in—

Figure 1, a side view; Fig. 2, a section on line *a b* of Fig. 1.

This invention relates to a design for bird- 15 cage hooks; and the design consists in the configuration and ornamentation of the hook as herein shown and described.

The design consists of a flat bar A, which is

bordered at its upper and lower edges by a wide rope-like flange B, the outer ends of 20 which merge together and are curved to form a hook C beyond the outer end of the bar. The surface of the bar is ornamented by a series of cruciform perforations D, all as shown in the accompanying illustration.

I claim—

The design for a bird-cage hook as herein shown and described.

In testimony whereof I have signed this specification in the presence of two subscribing witnesses.

ANDREW B. HENDRYX.
